(57) **CLAIM**

The ornamental design for a power strip, as shown and described.

DESCRIPTION

FIG. 1 is a front perspective view of a power strip of the first embodiment, showing my new design;

FIG. 2 is a rear perspective view thereof of the first embodiment;

FIG. 3 is a front view thereof of the first embodiment;

FIG. 4 is a rear view thereof of the first embodiment;

FIG. 5 is a left side view thereof of the first embodiment;

FIG. 6 is a right side view thereof of the first embodiment;

FIG. 7 is a top view thereof of the first embodiment;

FIG. 8 is a bottom view thereof of the first embodiment;

FIG. 9 is a front perspective view thereof of the second embodiment;

FIG. 10 is a rear perspective view thereof of the second embodiment;

FIG. 11 is a front view thereof of the second embodiment;

FIG. 12 is a rear view thereof of the second embodiment;

FIG. 13 is a left side view thereof of the second embodiment;

FIG. 14 is a right side view thereof of the second embodiment;

FIG. 15 is a top view thereof of the second embodiment;

FIG. 16 is a bottom view thereof of the second embodiment;

FIG. 17 is a front perspective view thereof of the third embodiment;

FIG. 18 is a rear perspective view thereof of the third embodiment;

FIG. 19 is a front view thereof of the third embodiment;

FIG. 20 is a rear view thereof of the third embodiment;

FIG. 21 is a left side view thereof of the third embodiment;

FIG. 22 is a right side view thereof of the third embodiment;

FIG. 23 is a top view thereof of the third embodiment; and,

FIG. 24 is a bottom view thereof of the third embodiment.

The broken lines in the drawings illustrate the portions of the power strip, which form no part of the claimed design.

1 Claim, 24 Drawing Sheets
